UNITED STATES PATENT OFFICE

2,610,731

PAINTBRUSH ATTACHMENT

Samuel Austin, Hartford, Conn.

Application October 10, 1949, Serial No. 120,596

5 Claims. (Cl. 206—15.1)

1

This invention relates to new and useful improvements in attachments for paint brushes and the primary object of the present invention is to provide a device that will support the head of a brush raised above the bottom wall of a container and thereby prevent the sediment on the bottom wall of a container from contacting the bristles of a brush.

Another important object of the present invention is to provide a pair of clamping members that are yieldingly held against the head of a brush and which members are perforated to permit turpentine, kerosene or the like to circulate freely through the members and a brush received by the members.

A further object of the present invention is to provide a device for retaining the head of a brush raised above the bottom wall of a container and which is quickly and readily applied to or removed from the head of a brush in a convenient manner.

A still further aim of the present invention is to provide a paint brush attachment that will increase the life of a paint brush and which is simple and practical in construction, strong and reliable in use, neat and attractive in appearance, small and compact in structure, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the present invention applied to a brush;

Figure 2 is a longitudinal vertical sectional view of the present invention and with dotted lines showing the pressure plate moved away from the base plate;

Figure 3 is a transverse horizontal sectional view taken substantially on the plane of section line 3—3 of Figure 2; and,

Figure 4 is an enlarged detail sectional view taken substantially on the plane of section line 4—4 of Figure 3.

Referring now to the drawings in detail, wherein for the purpose of illustration, there is disclosed a preferred embodiment of the present invention, the numeral 10 represents the present brush attachment generally, including an elongated substantially rectangular and perforated base plate 12 having spaced parallel side portions or flanges 14. The flanges 14 are provided with

2

outer side edges 16 that slope downwardly toward the lower end portion of the base plate 12.

A pair of spaced parallel transverse slots 18 are provided in the outer edges 16 of each of the side flanges 14 and the material between these slots 18 constitute tongues or arms 20 having depressions 22 for a purpose which will later be more fully described. The tongues 20 are disposed intermediate the ends of the flanges 14 as shown best in Figures 1 and 2 of the drawings.

Adjacent the upper edges of the side flanges 14 there is provided further slots or notches 24 and the material between the slots 24 and the upper edges of the side flanges 14 constitute tongues or arms 26 having depressions 28 that will bear against the side edges of a brush head 29.

A transverse stop 30 is provided at the lower end portion of the base plate 12 and the stop 30 is also perforated to permit turpentine, kerosene or the like to circulate therethrough. A bearing extension 32 depends from the stop 30 and will rest against the bottom wall of a container in order to retain the base plate 12 and stop 30 raised above the bottom wall of a container when the instant structure is in use.

A pressure plate 34 is associated with the base plate 12 and the pressure plate 34 is perforated to permit turpentine, kerosene or the like to circulate freely through the plates 12 and 34 as well as a brush disposed between the plates 12 and 34. The pressure plate 34 is provided at its lower end with a pair of ears 36 having trunnions or pivots 38 thereon that enter apertures 40 provided in the lower ends of the side flanges 14. A finger grip 42 is provided at the upper end of the pressure plate 34 and constitutes a means whereby the pressure plate may be moved away from the base plate 12 for the insertion of the brush 29 between the plates 12 and 34.

In practical use of the present invention, the plate 34 is swung outwardly from the plate 12, to its dotted line position as shown in Figure 2, whereupon the brush 29 is placed against the base plate 12 and between the side flanges 14. The depressions 28 of the fingers 26 will yieldingly bear against the side edges of the brush head 29 in order to retain the base plate 12 relative to the brush head.

Next, the pressure plate 34 is moved against the brush head and is held clamped against the brush head by the fingers 20, it being understood that the depressions 22 will bear against the outer face of the plate 34 in order to retain the same urged against the brush head. Next, the instant attachment and brush are inserted into a suitable

container having turpentine, kerosene or the like therein and the bearing extension 32 will contact the bottom wall of the container in order to retain the brush head and plates 12 and 34 raised above the bottom wall of the container.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A device for retaining the head of a brush raised above the bottom of a container, said device comprising an elongated base plate having upper and lower end portions, a stop at the lower end portion of said base plate for limiting downward sliding movement of a brush relative to said base plate, a bearing extension projecting laterally from said stop and offset from said base plate, a pressure plate hinged to the lower end portion of said base plate, means forming an integral part of said base plate for attaching the base plate to a brush head and for also retaining the pressure plate toward the base plate, and means forming part of said base plate for confining a brush relative to the base plate and also retaining the pressure plate in juxtaposition with the base plate.

2. A device for retaining the head of a brush raised above the bottom of a container, said device comprising an elongated base plate having upper and lower end portions and side flanges, a stop at the lower end portion of said base plate and extending transversely of said base plate and between said side flanges for limiting downward sliding movement of a brush relative to said base plate, a bearing extension projecting laterally from said stop and offset parallel to said base plate, a pressure plate hinged to the side flanges at the lower end portion of said base plate, said base plate and said pressure plate being perforated to permit a fluid to circulate therethrough, means for retaining the plates clamped against a brush head, and spring means on the base plate for clampingly attaching the base plate to a brush head.

3. A device for retaining the head of a brush raised above the bottom of a container, said de-

vice comprising an elongated base plate having upper and lower end portions and spaced side flanges, a stop at the lower end portion of said base plate and extending between said side flanges for limiting downward sliding movement of a brush relative to said base plate, a bearing extension projecting laterally from said stop and offset parallel to the base plate, a pressure plate hinged to the lower end portion of said base plate, said base plate and said pressure plate being perforated to permit a fluid to circulate therethrough, means for retaining the plates clamped against a brush head, said last named means including a pair of spring arms carried by said base plate and having curved lips for gripping said pressure plate, and a pair of coacting resilient members on said base plate for clampingly retaining a brush head against the base plate.

4. A device for retaining the head of a brush raised above the bottom of a container, said device comprising an elongated base plate having upper and lower end portions and side flanges, the lower end portion of said base plate being offset, a pressure plate hinged to the side flanges adjacent the lower end portion of said base plate, a pair of spring arms on said base plate alongside of said flanges and having protuberances intermediate their ends under which the side edges of the pressure plate are received to retain the pressure plate relative to the base plate and against pivotal movement, and an additional pair of spring arms on the base plate for yieldingly gripping a brush head to hold the latter relative to the base plate.

5. The combination of claim 4 wherein said pressure plate is received between said flanges and includes a lower end, a pair of opposed ears on the lower end of said pressure plate, a trunnion on each ear, the lower ends of said side flanges having registering apertures therein receiving said trunnions.

SAMUEL AUSTIN.
